UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

BINDING-POST.

No. 895,747.

Specification of Letters Patent. Patented Aug. 11, 1908.

Application filed October 5, 1906. Serial No. 337,595.

To all whom it may concern:

Be it known that I, MONROE GUETT, a citizen of United States of America, residing at Hartford, in the county of Hartford and 5 State of Connecticut, have invented certain new and useful Improvements in Binding-Posts, of which the following is a specification.

My invention relates particularly to a 10 novel means for securing circuit wire in a binding post.

In the drawings.—Figure 1 is a lateral sectional view of the binding post. Fig. 2 is a top view. Fig. 3 is a side view showing the 15 bore. Fig. 4 is a lateral view showing the circuit wire in place.

In carrying out my invention I provide a post *a* of the usual construction of such devices, having a bore *b* to receive the circuit 20 wire. In the side of said post there are openings *c c* in which non-rotating studs *d d* are located. The studs are preferably secured together by a bridge *e*. A screw *f* shoulders on said bridge and is threaded into the post 25 *a*, providing a means for forcing the studs inward to hold the circuit wire *g* in place.

In the usual construction an ordinary screw is used to hold the wire. This screw as it rotates cuts and spreads a stranded wire and is objectionable for this reason; in my 30 device the non-rotatable studs alone come in contact with the wire and consequently the wire is not cut and spread but is held firmly and even against the post so that a positive even contact is assured.

35

I claim as my invention:

A cylindrical binding post having a central bore and two openings through the wall of said post into said bore, non-rotatable binding studs movable lengthwise through 40 said openings, a bridge connecting the outer ends of said studs, and means connected with said bridge for moving said studs, substantially as described.

In testimony whereof I affix my signature 45 in presence of two witnesses.

MONROE GUETT.
